GEORGE W. PARSONS, OF HARRISBURG, PENNSYLVANIA.

Letters Patent No. 77,209, dated April 28, 1868.

IMPROVEMENT IN STRAW-CUTTERS.

The Schedule referred to in these Letters Patent and making part of the same.

TO ALL WHOM IT MAY CONCERN:

Be it known that I, GEORGE W. PARSONS, of Harrisburg, in the county of Dauphin, and State of Pennsylvania, have invented a new and useful Improvement in Straw-Cutters; and I do hereby declare that the following is a full, clear, and exact description of the construction and operation of the same, reference being had to the accompanying drawings, in which—

Figure 1 of plate 1 is a view of the right-hand side of the machine.

Figure 2 of plate 1 is a side view of internal gear-wheel and pinions.

Figure 3 of plate 1 is a plan or top view of the machine.

Figure 4 of plate 1 is a view in detail, showing the manner of attaching crank to the driving-gear wheel.

Plate 2.

Figure 1 is a view of the left-hand side of the machine.

Figure 2 is a top view in detail of balance-wheel and its attachments on knife-shaft.

Figures 3 and 4 are sectional views of feed-roller disks, with teeth dove-tailed therein.

Figure 5 is a detailed view, showing the manner in which the teeth of the disks engage each other.

Like letters in the different figures of the drawings represent like parts.

The nature of my invention consists in—

First, operating the feed-rollers by means of a short shaft of a knife-driving gear-wheel, supported by a movable and adjustable brace, the end of said shaft being provided with pinions of different sizes, so arranged, in combination with an internal gear-wheel on the shaft of the lower feed-roller, that different lengths of cuts of the straw or other material may be obtained.

Second, communicating motion from the lower to the upper feed-roller by means of two circular plates or disks, engaging one another by peculiarly-constructed teeth, of malleable iron, with dove-tailed shanks, suitably arranged on the face sides of the disks, in the casting or moulding thereof, the said gearing operating the upper with the lower roller, and allowing the necessary play for different thicknesses of straw or other materials to pass between the rollers in feeding the machine.

Third, counterbalances on the arms of the knife-shaft, opposite to the knife, and so that they can be removed, and another knife attached in their place.

Fourth, the manner of causing the fly-wheel to revolve with the shaft, by means of radial ribs on the end of the hub of the wheel, fitting similar ribs on a fixed washer, in combination with an elastic washer and a metallic screw-nut, or by inserting wooden pins in holes through the wheel and the driving-washer, or by a pin through the shaft engaging with the wheel, so that the fly-wheel may continue to revolve independently of the shaft, in case of sudden stoppage of the knife, and thus avoiding liability of injury to the knife or other part of the machinery.

Fifth, the manner of securing the crank to the driving-wheel by one screw or rivet, the crank having small lugs or flanges engaging the arm of the wheel.

To enable others skilled in the art to make and use my invention, I will proceed to describe the construction and operation of the same.

I construct my straw-cutter with a frame, A A, and box B, and feeding-rollers C C', (represented by dotted lines in fig. 1 of plate 1,) and place across the frame, in suitable bearings, a knife-shaft, D, similar to the machines now in use. To arms on the knife-shaft I attach a curved-cylindrical knife, E, and place on arms opposite to each end of the knife removable weights, F F, to counterbalance the weight of the knife and its attachments, the counterbalances being held in place by screws or bolts, so that they can be removed when it is desired to increase the cutting capacity of the machine, and another knife attached in the same place. The knife is made adjustable, to meet the bar or fixed cutter-plate, by being attached to arms provided with slots, and screw-bolts inserted through the slots, and into the fixed arms of the shaft, thus allowing the knife to be moved up or down on the fixed arms, and set to the position desired. I find it more desirable to have the knife

adjustable than the bar or cutter-plate, as in other machines, as it can be adjusted with more convenience than the cutter-plate.

The feeding-roller C is smooth, and revolves below and behind the cutter-bar G, in fixed bearings. The feeding-roller C' is ribbed longitudinally, and is held in position above the lower roller C by means of cheek or side pieces, with slots for the play of the shaft of the roller, and is held down on the material by means of spring or springs.

On the right-hand end of the shaft of the lower roller C, I place an internal gear-wheel, H, which may be as small or as large as desired. I use one seven inches in diameter.

A small cog-pinion, I, is placed on the right-hand end of the knife-shaft D. This pinion meshes with a large cog-wheel, K, to which the handle or crank L is attached, when the machine is operated by hand. Other power may be applied, by belt on the balance-wheel M or on a small pulley that may be attached to the wheel. The crank L has small flanges, a a, projecting, so as to engage and clasp one of the arms of the wheel K, and is held to its place by a single screw or rivet, b.

The wheel K is secured upon the outer end of a short shaft, c, which shaft is supported by a movable and an adjustable brace, N, the front end of which brace is held in place by the knife-shaft passing through it. The other end of the brace is made with a vertical slot, d, and secured by a screw or bolt, e, to the frame A. The brace may also be made so that both ends thereof are secured directly to the frame, or in any other manner, provided it is so made as to be movable and adjustable.

The inner end of the shaft c of the driving-wheel K is made with a small cog-pinion, O, which engages and meshes with the internal gear-wheel.

When an internal gear-wheel of small diameter—say seven inch diameter—is used, in order to get as short a length of cut as is desirable, the pinion must be so small that it can only be made by casting it on the end of the shaft c. To make a change in the length of the cut of the straw, I employ another small pinion, P, which is attached by unfastening the slotted end of the brace N, and moving the brace outward, so that the second pinion, P, may be slipped over the small pinion, O, on the end of the shaft, the internal part of the pinion P being made the proper size and shape to fit on the small pinion, O, and by replacing and securing the brace N, pinion P engages and meshes in the internal wheel.

By making the internal gear-wheel large enough, a pinion sufficiently small may be made separately, and properly attached to the end of the shaft c, instead of being cast on the end of the shaft, as hereinbefore described, in which case the pinions may be changed as required, for securing different length of cuts, by removing one, and substituting another of a smaller or larger size.

In order to communicate motion from the lower to the upper feed-roller, I employ a disk, R, or circular plate, on the shaft of each roller, the plates facing each other, and are constructed with cog-teeth, f f f, arranged around on the face sides. These cog-teeth are peculiarly shaped, being triangular-shaped, with rounded ends, and project from the sides of the plates, being disconnected from the hub, so that the outer ends of the teeth on the driving-disk may act on the inner ends of those on the driven disk, and vice versa, as shown by fig. 5 of plate 2. The cog-teeth being disconnected with the hub, and being subjected to considerable strain in use, may be frequently broken if made of cast iron, of which the plates or disks are made. I therefore make the teeth of malleable iron, with dove-tail shanks, which are held in the plates by being placed in the moulds of the same before the moulds are filled with the molten iron.

As the knife-shaft revolves with rapidity, the knife and other parts of the machine are exposed to injury from the momentum of the fly-wheel, when the knife may be suddenly arrested by a solid substance in the straw or other material. To prevent such injury in such cases, I employ three different devices, any one of which or all of them may be used at one time.

First. The fly-wheel M is placed on the shaft, against a shoulder on the shaft, having at said shoulder a hole, g', through the shaft, in which a wooden pin is placed, each end of which projects into a slot across the hub of the wheel, the wheel being held laterally by washers and a screw-nut on the end of the shaft. When the knife is suddenly arrested, the momentum of the fly-wheel will break the wooden pin before breaking any part of the machine.

Second. I place on the shaft, outside of the hub of the wheel, a washer, S, which has a square hole to fit a square place on the shaft, so that it will always revolve with the shaft, and I make one or more coinciding holes, h, through said washer and hub of the wheel, in which wooden pins are placed. The momentum of the wheel will break these pins before breaking the machine, in case of a sudden stoppage of the knife.

Third. On the outer end of the hub of the fly-wheel I make a series of radial ribs or corrugations, and make similar ribs on the inside face of the washer S, with square hole, (which I call a driving-washer,) and hold the driving-washer against the hub of the wheel by a screw-nut, T, on the shaft, with an elastic washer, j, between the driving-washer and the nut. When the knife-shaft is suddenly stopped, the radial ribs on the wheel-hub will slip over and pass by those on the driving-washer, the elastic washer allowing the driving-washer to move outwardly on the shaft sufficiently for that purpose.

Operation.

The operator, standing on the right-hand side of the machine, turns the crank L, attached to the driving-wheel K, with the right hand, and with the left hand adjusts the material in the box, B, so that the feed-rollers move the material to the knife.

The different lengths of cuts are obtained by changing the pinions on the end of shaft c, as described in the specification.

It is obvious that my improved machine is adapted to the cutting of various other materials besides straw.

such as corn-husks and stalks, hay, stems and leaves of tobacco, &c., and I do not desire to restrict myself to the use of my improvement in cutting straw alone.

Claims.

Having thus fully described my invention, what I claim therein as new, and desire to secure by Letters Patent, is—

1. The pinion O, on the end of the shaft *c* of the driving-gear wheel, in combination with the movable and adjustable brace N.
2. The internal gear-wheel H, in combination with the driving-gear wheel K, whose shaft is supported by a movable and adjustable brace, as set forth.
3. The movable and adjustable brace N, supporting the large gear-wheel K, in combination with the cog-pinion I on the knife-shaft D.
4. The pinion P, fitting on and over the pinion O, in combination with the shaft *c* and driving-gear wheel K.
5. The combination, in a straw-cutter, of a feed-roller whose shaft moves up and down, with the driving-gear wheel K and pinion O, when said wheel and pinion are supported by an outside brace.
6. The employment of detachable counterbalances F F on the arms of the knife-shaft D, when combined with a single adjustable rotary knife.
7. Operating the feed-roller C' of a straw-cutter by means of the disks R, when constructed with cog-teeth *f f f*, disconnected radially from the hubs thereof, in the manner and for the purpose as described.
8. The screw-nut T, elastic washer *g*, and fixed driving-washer S, with radial ribs, in combination with the radial ribs on the hub of the fly-wheel, substantially as described.
9. The construction of the hub and fixed driving-washer, with holes, *h*, for the insertion of wooden pins, substantially as described.
10. The construction of the shaft, with a hole, *g'*, for the insertion of a wooden pin, with the slot across the hub of the fly-wheel, substantially as described.
